UNITED STATES PATENT OFFICE.

EUGENE W. HAWLEY, OF PHILADELPHIA, PENNSYLVANIA.

WARDROBE TRUNK.

Application filed June 5, 1922. Serial No. 566,042.

To all whom it may concern:

Be it known that I, EUGENE W. HAWLEY, a citizen of the United States, residing at Philadelphia, county of Philadelphia, and 5 State of Pennsylvania, have invented a new and useful Improvement in Wardrobe Trunks, of which the following is a full, clear, and exact description, reference being had to the accompanying drawings, which 10 form a part of this specification.

My invention relates to an improvement in wardrobe trunks and in particular to means whereby the contents of the hanger or clothes compartment may be secured against theft.

15 Wardrobe trunks are usually constructed with two hinged together body sections, in one of which is fitted drawers and the other of which is provided with means for supporting clothes hangers, adaptable for the 20 support of garments, as in a closet. It is usual to provide a press or follower supported at its ends by brackets on the sides of the compartment and adapted to confine or press together the lower portion of garments 25 carried by the hangers.

When the trunk is opened, by separating the body sections, the drawer and clothes compartments are exposed and access thereto may be readily had unless the body sections be again brought together and locked. In order to permit of persons leaving their trunks open, in hotels for example, without risk of losing articles of value by theft, a 35 variety of devices have been perfected for locking the drawers in the drawer compartment so that they cannot be opened even though the trunk be open.

Although care has been taken to provide means for locking the drawers in a wardrobe 40 trunk, so that the trunk body may be left open with security against theft, no means have as yet been provided for securing the garments in the clothes compartment, and it has frequently been the experience of travellers, where they have left their trunks open, that garments have been removed from the clothes compartments. In the present type 45 of trunk, if it be left open, the garments may be so readily removed that they serve as a temptation to theft, by that class of thief which would not force a lock or leave positive evidence of his act by damaging the trunk itself.

Now the object of my invention is to provide 50 means whereby the follower or press may be securely locked to the body of the

trunk and prevent the unauthorized removal of garments from the clothes compartment.

Having now, in a general way, indicated the nature, purpose and advantages of my 60 invention, I will proceed to describe a preferred embodiment thereof with reference to the accompanying drawings, in which—

Fig. 1 is a perspective view of a wardrobe trunk in open position and embodying my 65 invention.

Fig. 2 is a cross-sectional view of the clothes compartment of the trunk shown in Fig. 1.

Fig. 3 is a vertical sectional view of the 70 clothes compartment of the trunk shown in Fig. 1.

Fig. 4 is an enlarged fragmentary view, partly in section, showing a detail of my invention.

Fig. 5 is a fragmentary view of one of the 75 follower bar support brackets, looking in the direction of line 5—5 Fig. 4.

Fig. 6 is a fragmentary view showing the other follower bar support bracket, looking 80 in the direction of lines 6—6 Fig. 4.

The trunk comprises a section A in which is a tier of drawers *a* and a section B hinged to the section A along the edge and provided with a hinged top *c*. The front edges of the 85 section B may be reinforced by means of strips *b*, and the edges of the sections A and B, adapted to be brought together when the trunk is closed, are provided with the usual locking means, not shown. The compartment B may contain a shoe box *u* as shown.

Suitably mounted within the section B adjacent the upper end thereof are a pair of rods *d* adapted for the support of garment hangers *e*. Spaced below the rods *d* and secured to opposite sides of the compartment B, at an angle, are brackets *f* and *g* adapted for the support of a follower bar *h*. The bracket *f* is formed with a raised body portion, provided with equally spaced closed slots *i* and with flanges *j*, which permit it to be secured to the trunk. The bracket *g*, which is positioned opposite to bracket *f*, is formed with a raised body portion provided with equally spaced slots *k* open at their 105 lower ends, and equally spaced closed slots *l*, relatively spaced from slots *k*.

The follower bar *h* has ends *m*, *m'* and is provided adjacent its end *m'* with a lock *n*, the bolt *o* of which is adapted, when in locking position, to extend behind and parallel to end *m'*. The bar *h* is placed in position

by first inserting the end *m* in one of the closed slots *i* of bracket *f* and then inserting the end *m'* upwardly into one of the open slots *k* in bracket *g*. If the reinforcing strips *b* are used, the strip adjacent the bracket *g* is cut out as at *p* for the passage of the end of bar *h*.

When the bar is in position with its ends *m* and *m'* in slots *i* and *k*, respectively, the 10 bar may be locked in position by means of lock *n*, the bolt *o* of which is extended into one of the closed slots *l* by means of a key *t*.

It will now be observed that the bar *h* is 15 irremovably held in the brackets *f* and *g* since the lock bolt *o* prevents the end *m'* from dropping down out of slot *k*. The garments carried by the hangers *e* cannot be removed therefrom, if before locking the bar *h* in position it be forced back against the clothes 20 so as to secure them tightly against the back of the compartment.

If desired, my invention may be applied to a more complete follower, such as illustrated, comprising an apron *q* secured at one 25 end to the back of the compartment B and extending over the hangers *e* to a point in the lower portion of the compartment, the apron *q* having secured to it a bar *r*, connected to bar *h* by means of springs *s*. The 30 bar *h*, when locked as above described, will not only directly tend to prevent the removal of garments from compartment B, but will cause the apron to act likewise.

Having now fully described my invention, 35 what I claim and desire to protect by Letters Patent is:

1. The combination with a wardrobe trunk comprising sections hinged together, one of 40 which provides a compartment for garments, of hangers for the support of garments in said compartment, a follower, means providing a multiplicity of elements along a side wall of the compartment and adapted to be engaged by and position the 45 follower at different distances from the rear wall of the compartment, a locking member carried by the follower, and a multiplicity of complementary locking elements along a side wall of the compartment so located as 50 to be respectively engageable by said locking member in different positions of the follower.

2. The combination with a wardrobe trunk comprising sections hinged together, one of 55 which provides a compartment for garments, of hangers for the support of garments in said compartment, brackets on opposite side walls of the compartment, a fol-

lower adapted to extend across the compartment, each of said brackets having a multiplicity of follower-engaging and positioning elements, a locking member carried by the follower, and a multiplicity of complementary elements carried by one of the brackets and so positioned that one of them is engageable by said locking member after the follower is engaged with and positioned on the brackets.

3. The combination with a wardrobe trunk comprising sections hinged together, one of which provides a compartment for garments, of hangers for the support of garments in said compartment, a follower bar adapted to extend across the compartment, brackets, on opposite side walls of the compartment, each having a series of orifices with which the corresponding end of the follower bar is adapted for engagement and thereby positioned, one of said brackets having a second series of orifices, and a key-controlled locking bolt carried by the follower bar and adapted, when the follower bar is so positioned relatively to said brackets, to align with one of the said second series of orifices, whereby, when the trunk is open, the follower bar may be locked after it has been so engaged with and positioned on the brackets.

4. The combination with a wardrobe trunk comprising sections hinged together, one of which provides a compartment for garments, of hangers for the support of garments in said compartment, brackets on opposite side walls of the compartment, one bracket having a series of closed slots, the other bracket having a series of slots open at one end and a series of closed slots, a follower bar one end of which is adapted to be inserted in one of the closed slots of the first bar and the other of which is adapted to swing into engagement with the open-ended slots of the second bar, whereby the follower bar is positioned and the garments may be held compressed toward the rear wall of the compartment, and a key-controlled locking bolt carried by the follower bar and adapted, after the follower is so positioned, to be moved into engagement with one of the closed slots of the second bar, thereby locking the garments from ready removal when the trunk is open.

In testimony of which invention, I have hereunto set my hand, at Philadelphia, Pa., on this 29th day of May, 1922.

EUGENE W. HAWLEY.
